NATHAN F. BURNHAM, OF YORK, PENNSYLVANIA.

Letters Patent No. 72,450, dated December 24, 1867.

IMPROVEMENT IN GUIDES FOR WATER-WHEELS.

The Schedule referred to in these Letters Patent and making part of the same.

TO ALL WHOM IT MAY CONCERN:

Be it known that I, NATHAN F. BURNHAM, of York borough, in the county of York, and State of Pennsylvania, have invented certain new and useful Improvements in the Construction of Cases and Guides for Turbine Water-Wheels; and I do hereby declare that the following is a full, clear, and exact description thereof, reference being had to the accompanying drawings, making a part of this specification, in which—

Figure 1 is a top view of the devices for adjusting the water-guides.

Figure 2 is a side elevation of the same.

Figure 3, sheet 2, is a section taken in the horizontal plane, indicated by red line yy in fig. 2.

Figure 4, sheet 2, is a section, taken in the vertical planes, indicated by the course of red line xx in fig. 1. Similar letters of reference indicate corresponding parts in the several figures.

This invention relates to a novel mode of shaping, pivoting, and arranging the guides, which form the water-passages leading into the wheel-case, whereby unobstructed converging passages are formed, which will guide and direct the water upon the buckets or floats of the wheel within the case, in the most advantageous manner, as will be hereinafter described.

To enable others skilled in the art to understand my invention, I will describe its construction and operation.

In the accompanying drawings, A and B represent two rings, which are secured together by means of posts $a a$, in planes parallel to each other, and at such a distance apart as to receive between them the guides which form the water-inlet passages. The lower ring A is constructed with a cylinder or band, A', upon it, which projects down far enough to receive a cross, which holds the step for the water-wheel shaft to rest upon, and said ring is turned out in a suitable manner to receive the water-wheel. The ring B, which is above the ring A, forms the top of the water-way, and also a part of the top of the wheel-case. The interior diameter of this ring B is very slightly larger than the diameter of the water-wheel, so that the wheel will turn freely therein, and admit of being lifted out of the wheel-case when the cap thereon is removed. The cap C is a ring, which fits tightly upon the ring B, and is bolted fast thereto by screws and nuts $b^2 b^3$, as shown in fig. 4. This cap has a central dome, C', formed on it, in which the journal-box is applied for the shaft of the water-wheel. On top of the cap C is a ring, D, which is supported in a position concentric to the axis of the circular wheel-case, and which is of less diameter than the cap over which it is arranged. At regular distances apart around this ring D, short arms, $b b$, are pivoted to its bottom side by vertical pivots. The outer ends of these arms are pivoted to studs $b^1 b^1$, which project through slots $d d$, made through the top ring B, which studs are formed on the upper edges, and near the outer curved ends of pivoted guides G G', as shown in the drawings. The arms $b b$ can be readily slipped up over the studs $b^1 b^1$. The ring D is centred and supported in position, by means of flanged rollers, arranged so as to receive and bear against the interior edge of the ring, which rollers $g g$ have their lower bearings in the cap-ring C, and their upper bearings in brackets $c c$, secured to the dome C' of said ring. This ring D is moved about its axis by means of a vibrating arm, e, which is secured at its outer end to a vertical shaft, h, which has a square head for receiving a key-rod, and which turns freely between a bracket, h', and the ring B. The inner end of the arm e is pivoted to the ring D by means of a vertical pin, i, which passes through an oblong slot, through said arm, and enters the ring, as shown in fig. 1. By turning the shaft of arm E partially around toward the right or the left, the guides G G may all be moved together, and the passages for the entrance of water into the wheel-case increased or diminished, or completely closed. Instead of employing the arm e for moving ring D, a toothed pinion may be used in its stead; and a segment-rack secured to this ring, which will engage with the teeth of the pinion. The guides G G may be varied in number, according to the diameter of the case, and the amount of water to be admitted therein. These guides are curved inward about three-fourths their length, and outward about one-fourth their length. They are pivoted to vertical bolts j , which pass through both rings A and B, and also through ears $k k$, which are formed on the outer faces, and near the inner ends or termini of the guides, as shown in the drawings. These guides are of an equal length and of uniform shape, and they are of such length that, when shut, as shown in blue lines, fig. 5, their outer flaring ends will overlap the inner ends of the guides nearest them. The inner faces of these guides are concave, so that water directed against these surfaces will be conducted onward toward the inner ends of the guides, while acting upon the floats of the wheel within the case. The outer ends of these guides

are turned outward, so as to form, in conjunction with the external bevelled surfaces yy , and inner ends of the guides nearest them, flaring throats or passages, for the passage of water in straight lines to the buckets of the water-wheel.

It will be seen, by reference to fig. 5, that the water entering any one of the passages formed by two of the guides will take the course indicated by the arrow, which is a straight line nearly tangential to the circumference of the water-wheel within the case. If the guides G were made straight or flat on their inner surfaces, instead of concave, as shown, other things being equal, then the water would be obstructed or dammed at the entrance of the throat, and the currents would take a course more direct toward the centre of the wheel-case. By having the guides curved and arranged as shown and described, very little or no obstruction will be offered to the passage of water into the wheel-case, and the force of the water will be directed to a much better advantage upon the floats of the wheel. The mere curving of the guides alone, as above described, would not secure the straight flow of the water in direct lines; hence I have made the external surface of the inner ends of the guides bevelled, instead of curved, as heretofore; and it is by means of this combination of curved and straight surfaces that the end desired is secured.

Having described my invention, what I claim as new, and desire to secure by Letters Patent, is—

The guide constructed with a bevelled surface, as at y , such bevelled surface forming one side of the entire throat, formed by the respective pairs of guides, substantially in the manner and for the purpose described.

NATHAN F. BURNHAM.
